(57) **CLAIM**

The ornamental design for an electronic device, as shown and described.

DESCRIPTION

FIG. 1 is a rear perspective view of my new design for an electronic device;

FIG. 2 is a rear elevation view thereof;

FIG. 3 is a front elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is an enlarged rear perspective view of a portion of FIG. 1; and,

FIG. 9 is an enlarged rear perspective view of the inner encircled portion of FIG. 8.

The even length dashed lines in the figures illustrate portions of the electronic device that form no part of the claimed design.

The uneven length dot-dash lines in FIGS. 1 and 2, and the outer uneven length dot-dash lines in FIG. 8, represent a boundary line that forms no part of the claimed design.

The inner uneven length dot-dash broken lines in FIG. 8, and the uneven length dot-dash broken lines in FIG. 9, encircle portions of the claimed design that are illustrated in an enlargement and form no part of the claimed design.
